UNITED STATES PATENT OFFICE

2,470,391

TATTING SHUTTLE

Hilbert B. Daniello, Allentown, Pa.

Application April 18, 1947, Serial No. 742,390

1 Claim. (Cl. 87—58)

1

This invention relates to tools for fancy work, and more particularly, to a tatting shuttle to be used for such work.

A main object of the invention is to provide a tatting shuttle equipped with a rotatable bobbin to hold the thread used for tatting.

Another object of the invention is to provide a tatting shuttle of the character indicated above, wherein the rotatable bobbin has a crank to facilitate winding of the thread on the bobbin.

A further object of the invention is to provide tatting shuttle of the character indicated above, wherein the rotatable bobbin is adapted to be wound by a detachable crank.

Other objects of the invention will appear in the following specification describing the invention, with particular reference to the accompanying drawings.

It is, however, to be understood that the invention is not to be limited or restricted to the exact construction and combination of parts described in the specification and shown in the drawings, but that such changes and modifications may be made as fall within the scope of the claim appended hereto.

In the drawings:

Figure 1 is a front view of a tatting shuttle according to the invention.

Figure 2 is a side view of the tatting shuttle shown in Figure 1.

Figure 3 is a vertical sectional view through the shuttle side walls showing a winding bobbin mounted in said side walls.

Figure 4 is a perspective view of a modified form of the tatting shuttle.

Figure 5 is a vertical sectional view through the bobbin used in the modified form of the shuttle shown in Figure 4.

With particular reference to the drawings, it will be observed that the shuttle comprises two side walls 10 centrally bowed out to form an enclosure therein. The two walls 10 may be integral at the top 11, but they may be welded or otherwise attached. At the bottom end 12, however, the two side walls 10 are separated from each other by cut 13. These members may be fabricated of plastic, wood, metal, or any other material having sufficient elasticity to provide a moderate frictional contact between the side walls 10 and the rims of the circular sides 17;

2

or these members may be fabricated of less elastic forms of the aforementioned materials, a simple spring being held between one side wall 10 and its adjacent circular side 17, the pressure of said spring providing the necessary frictional resistance to the motion of bobbin 15.

The mid-portions of the walls 10 are provided with two centrally located coaxial apertures 14. A winding bobbin 15 has a shaft 16 adapted to be journaled rotatably in the apertures 14 in the walls 10. The bobbin 15 comprises two circular sides 17 that are slightly spaced from the ends of the shaft 16 so as to be in frictional contact with the curved walls 10 of the shuttle.

An orifice 18 extends diametrically through the shaft 16 at its mid-portion. The purpose of this orifice 18 is to anchor the thread 20 on the bobbin 15, as will be described more particularly hereinafter.

One wall 10 of the shuttle is provided with a notch 19 to permit a thumb to engage one side 17 of the bobbin 15 to regulate the turning of the bobbin 15.

In the operation of the device illustrated in Figures 1, 2, and 3 of the drawings, the end of the thread 20 is inserted into the orifice 18 in the shaft 16 of the bobbin 15, and then the bobbin 15 is rotated by a thumb or finger in the notch 19. The bobbin 15 can be unwound in the same manner, or the frictional engagement between the sides 17 of the bobbin 15 and the walls 10 of the shuttle may be sufficient for this purpose. This frictional engagement may be lessened by spreading apart the walls 10 of the shuttle, and this may be effected by separating the walls 10 manually. If desired, a sheet of paper or other material may be inserted in the cut 13 at the bottom end 12 of the shuttle to spread the walls 10 apart a predetermined distance. To facilitate the insertion of this layer of paper or other material, the cut 13 has a slight bevel at the upper portions thereof.

A modified form of shuttle is illustrated in Figures 4 and 5. The shuttle of this modification is exactly the same as that described with relation to Figures 1, 2, and 3, but the bobbin is slightly different. One end of the bobbin shaft 21 has a tapped hole 23, and a crank 24 has a threaded end 25 adapted to engage the tapped hole 23 to facilitate the rotation of the bobbin 22,

The wall 10 of the shuttle has a suitable opening to permit the crank 24 to pass therethrough. This crank 24 is detachable, and the bobbin 22 may be used in the same manner as the bobbin 15 of the first form.

What is claimed is:

A tatting shuttle, comprising two walls of resilient material connected with each other at one end and severed from each other at the other end, the central portions of said walls having a pair of coaxial openings respectively formed therein, a bobbin having a shaft and, a pair of disc-shaped sides, respectively spaced inwardly from the ends of the shaft, said central portions of the walls being yieldably bowed outwardly away from each other to receive said bobbin therebetween with the ends of said shaft journaled in said openings in the walls and with the peripheral edges of said disc-shaped sides of the bobbin in yieldable frictional contact with the bowed surfaces of the walls, said walls normally being in abutting engagement with each

other at said severed end thereof whereby a spacer element may be inserted therebetween to decrease the friction between the bobbin and the walls, and the walls being bevelled at said severed ends thereof to facilitate the insertion of said spacer element.
